Patented Aug. 29, 1922.

UNITED STATES PATENT OFFICE.

WYATT MARTIN, OF CLEVELAND, OHIO, ASSIGNOR OF ONE-HALF TO CUMMING COX.

LOCK-WIRE TURNBUCKLE.

1,427,114.

Specification of Letters Patent. Patented Aug. 29, 1922.

Application filed June 17, 1918. Serial No. 240,442.

To all whom it may concern:

Be it known that I, WYATT MARTIN, a citizen of the United States, and a resident of Cleveland, county of Cuyahoga, State of Ohio, have invented a new and useful Improvement in Lock-Wire Turnbuckles, of which the following is a specification, the principle of the invention being herein explained and the best mode in which I have 5 contemplated applying that principle, so as to distinguish it from other inventions.

The present invention relates to lock-wire turn-buckles for holding the ends of wire cables and the like without soldering the 10 same. It is particularly adapted for use in securing cables, such as are used in aeroplanes, and the device is adapted to be formed as one end of the usual turn-buckle employed in such constructions.

20 The device combines light weight with strength and holding power and is easy to install or replace. When used cables may be changed readily and under conditions in which they could not be soldered.

25 Figure 1 is a side elevation of my improved turn-buckle; Fig. 2 is a central section through the turn-buckle; Fig. 3 is a side elevation partially in section of a modified form of turn-buckle; Figs. 4 and 5 are 30 sections taken on the lines 4-4 and 5-5 of Fig. 2, respectively; Figs. 6 and 7 are sections taken on the lines 6-6 and 7-7 of Fig. 3 respectively.

The present device consists of a chuck 35 portion 1 having a slotted end 2 provided with an aperture 3 adapted to receive a pin or other fastening means to hold it to a bracket or clip. The chuck is slotted centrally, the lower portion 4 of the slot being 40 narrowed and provided with inclined concave grooves 5 terminating in a double aperture 6 extending through the lower end of the chuck. The faces 7 of the slotted portion are flat and are provided with apertures 45 8 to lessen the weight. The particular outer form of the chuck is not essential and when used under conditions where light weight is not essential, the chuck will preferably be left with rounded faces and without the 50 apertures to simplify the manufacture and to lower the cost.

Below the inclined grooves 5, the chuck terminates in a cylindrical portion 9 which has an upper exteriorly threaded portion 10 55 and an extending split end 11 which is tapered toward the end. The double aperture

6 extends through the split end and over this end is mounted a sleeve 12 which is interiorly threaded at its upper end and is provided with faces 13 adapted to be engaged by a wrench or the like. The sleeve is provided with an inclined annular face 14 at its lower portion terminating in a centrally located aperture 15 of sufficient size to fit the cable 16. The inclined annular face 14 is adapted to contact with the inclined outer face of the split portion of the chuck in order to securely grip the wires when the sleeve is threaded on to the threaded portion of the chuck. 70

The cable 16 is adapted to be inserted through the split sleeve and is mounted over a grooved bobbin 19, and is then threaded downwardly again through the sleeve. The bobbin 19 is heart shaped and conforms to 75 the angle of the grooves in the chuck so that when the wires are clamped in the sleeve further movement of the wire will wedge the bobbin and the cable firmly in the inclined grooves in the chuck and prevent further 80 movement of the same.

In the form shown in Fig. 3 the threaded end 20 of the chuck is split and has two apertures 21, 22 opening together, one of them larger than the other. The cable 23 is 85 threaded through the sleeve and over the bobbin as in the other form, and extends down through the short end of the chuck, the stub end 24 of the cable being held in the smaller one 22 of the two openings. 90 This split threaded portion of the chuck is cone shaped and threaded on its outer surface, and is adapted to be engaged by a short sleeve 25 which will securely clamp the stub end of the cable between the two halves of 95 the chuck. Thus when any strain is put on the cable the stub end is firmly held and the cable will then move slightly until the bobbin 26 has wedged the two portions of the cable firmly against the grooves in the chuck, 100 holding the same tightly against movement.

The form of the present turn-buckle, as shown in Fig. 3, where the upper end of the chuck terminates in a threaded portion 27, is adapted to be engaged by one end of an interiorly threaded turn-buckle 28 carrying 105 the usual outer end provided with the usual slotted end 29. When in use it has been found that the long sleeve shown in Figs. 1 and 2 is not essential and the device will 110 hold the cable securely even if the sleeve is not employed, the cable being wedged firmly

against the two grooves in the chuck proper by means of the bobbin. All that is necessary is that the stub end of the cable should be held sufficiently tight so that when strain 5 is placed on the cable it will be maintained in its portion until the cable has pulled the bobbin down tight so as to lock the cable in the two inclined grooves. It is of course understood that the present turn-buckle will 10 be made in various sizes for different types of work, the size shown in Fig. 3 being designed for aeroplane construction where light weight is essential, while the forms shown in Figs. 1 and 2 will be used for 15 heavier types of cable where the weight is not so essential.

Other modes of applying the principle of my invention may be employed instead of the one explained, change being made as regards the mechanism herein disclosed, provided the means stated by any of the following claims or the equivalent of such stated 20 means be employed.

I therefore particularly point out and distinctly claim as my invention:—

1. In a device of the character described, the combination of a chuck member having a lower split portion provided with two cable receiving apertures, and a slotted upper 30 portion having inclined grooves in commu-

nication with such apertures, the exterior of such chuck member being apertured, and being provided at its lower end with a cone shaped portion, and a clamping sleeve having an interiorly threaded portion adapted 35 to be threaded on the chuck member, said sleeve having an inner inclined annular face adapted to contact with said cone shaped portion of said chuck member to clamp the cable in such apertures. 40

2. In a device of the character described, the combination of a chuck member having a lower split portion provided with two cable receiving apertures, and a slotted upper portion having inclined grooves in communication with such apertures, the exterior of such chuck member being apertured, a bobbin adapted to receive the cable therearound and being pointed to wedge the cable in such inclined grooves, and a clamping member 50 interiorly threaded and adapted to engage over said lower split threaded portion to clamp said cable in such apertures, said clamping member having a centrally placed aperture adapted to receive the extending 55 portion of said cable and maintain it in alignment with the device.

Signed by me, this 14th day of June, 1918.

WYATT MARTIN.
